DESIGN FOR AN ACCESSORY UNIT FOR COOKING STOVES

Herbert M. Reeves, Kankakee, and Jon W. Hauser,
Oak Park, Ill., assignors to Florence Stove
Company, Gardner, Mass., a corporation of Massachusetts

Application July 21, 1944, Serial No. 114,495

Term of patent 7 years

(Cl. D81—25)

To all whom it may concern:

Be it known that we, Herbert M. Reeves and Jon W. Hauser, citizens of the United States, residing at Kankakee, in the county of Kankakee and State of Illinois, and Oak Park, in the county of Cook and State of Illinois, respectively, have invented a new, original, and ornamental Design for an Accessory Unit for Cooking Stoves, of which the following is a specification, reference being had to the accompanying drawing forming a part thereof.

Fig. 2 is a front elevational view of the unit.

Fig. 3 is a side elevational view of the unit.

Fig. 4 is a sectional view taken in a vertical plane substantially on the line 4—4 of Fig. 2.

We claim:

The ornamental design for an accessory unit for cooking stoves, substantially as shown.

HERBERT M. REEVES.
JON W. HAUSER.
